INVENTOR:

O. Snow,
Rev
Alexander Mason
Attorney

United States Patent Office.

OTIS SNOW, OF BURLINGTON, VERMONT.

Letters Patent No. 95,158, dated September 21, 1869.

IMPROVEMENT IN BUTTER-WORKERS.

The Schedule referred to in these Letters Patent and making part of the same.

To all whom it may concern:

Be it known that I, OTIS SNOW, of Burlington, in the county of Chittenden, and in the State of Vermont, have invented certain new and useful Improvements in Butter-Workers; and do hereby declare that the following is a full, clear, and exact description thereof, reference being had to the accompanying drawings, and to the letters of reference marked thereon, making a part of this specification.

The nature of my invention consists in the construction and general arrangement of a "butter-worker," as will be hereinafter fully set forth.

In order to enable others skilled in the art to which my invention appertains to make and use the same, I will now proceed to describe its construction and operation, referring to the annexed drawings, in which—

Figure 1 is a longitudinal vertical section, and

Figure 2, a plan view of my invention.

A represents a triangular box, of suitable dimensions, the front of which is curved, or forms the segment of a circle, having the side of the box as radius.

This box may rest on legs or supports B B, as shown in fig. 1, or may have clamps or other suitable devices attached to it, to fasten it to a table, if so desired.

Near the inner corner of the box A, in its bottom, is pivoted a standard, C, the upper end of which is

slotted, so that the tenon *a* of a bar or lever, D, may be inserted therein, and pivoted to the same.

The lever D extends beyond the front curved side of the box A, and forms there a handle.

On the under side of the bar or lever D, near its ends, are secured two ears or projections, E E, in which the journals of a roller, F, have their bearings.

It will be seen that the standard C, turning on its pivot, allows the roller F to work over the whole bottom of the box, and, the bar D being pivoted in said standard, it can be raised up from the box whenever desired.

Having thus fully described my invention,

What I claim as new, and desire to secure by Letters Patent, is—

The box A, perforated, to admit the pivot of the standard C, roller F, ears E E, handle D, hinged, at *a*, to the standard C, and said standard pivoted through the bottom of box A, when all the parts are constructed and arranged substantially as herein set forth.

In testimony that I claim the foregoing, I have hereunto set my hand, this 8th day of May, 1869.

OTIS SNOW.
